UNITED STATES PATENT OFFICE.

CARL RACH, OF STAPLETON, NEW YORK.

ROTARY PRESS.

1,092,800.

Specification of Letters Patent.

Patented Apr. 7, 1914.

Application filed October 28, 1913. Serial No. 797,811.

To all whom it may concern:

Be it known that I, CARL RACH, a subject of the King of Prussia, and residing at Stapleton, in the county of Richmond and 5 State of New York, have invented a certain new and useful Improvement in Rotary Presses, of which the following is a specification.

The present invention relates to rotary 10 presses and particularly to brewers' presses of the type shown in my Patent 1,018,267, dated February 20, 1912.

The object of my invention is to improve 15 the rotary pressure disks by rendering them more efficient, lighter, easier to clean and repair, and at the same time more durable.

In the accompanying drawing, Figure 1 is a side elevation of a pressure disk with portions removed or broken away; Fig. 2 20 is a cross section thereof on the line 2—2, Fig. 1; Fig. 3 is a perspective of one of the segmental perforated web plates; and Fig. 4 is a perspective of one of the segmental screens.

25 In my patent above mentioned, I have shown a pressure disk with removable segmental facing screens. The body of the disk however is shown in common form with radial arms extending from hub to 30 rim and united by channeled webs, cast integral therewith. When it is desired to clean the press it has consequently been necessary, after the screen segments are removed, to wash out the interior of the press, 35 including the webs, by means of a hose introduced through the door of the press. This is not only awkward but inefficient, since it is possible in this manner to reach but one side of the webs and practically impossible to clean their outer faces and the 40 interior walls of the press. Furthermore, the webs being of cast iron and being subject to attack by the acids of the beer wort, it has been necessary to make them fairly 45 heavy, so that they may not be rapidly eaten away and the disk rendered useless. Furthermore, and partially for the same reason, it has been impracticable to make the channels as numerous as might be desired to let the liquid escape freely and in 50 view of their relative small capacity and liability to become clogged, it has been necessary to clean away frequently or to discharge the material imperfectly dried.

55 These defects have been remedied by the

present improvement which consists, briefly, in making the webs independent of the body of the disk, forming them of perforated plate metal, preferably of a substance which is not attacked by the acids of the beer 60 worts, and supporting them in seats on the face of the disk so that they may be easily removed with the segmental facing screens.

A suitable construction in which my invention is embodied, is illustrated in the accompanying drawing. As here shown the hub 10 is cast integral with the radial ribs 11 which connect the hub to the rim 12. A seat 13 is formed by offsetting the ribs, hub and rim surrounding the aperture or open 70 field 14 formed by omitting the usual web between these parts. A perforated rigid plate 15 shaped to this aperture and of a thickness substantially corresponding to the depth of the seat, rests in the latter with 75 its outer face substantially flush with the outer face of the disk. After the adjustment of the slide bars 16 the screen 17 is slid in above the plate 15 and serves to retain it in its seat. The retaining bar 18 prevents 80 the screen 17 from falling out.

A gear supporting ledge or ring 23 is cast integral with ribs 11 and is united with the rim 12 by fins 19 extending between the two. As here shown these fins serve the double 85 function of strengthening the ring 23 and of forming an auxiliary support for the perforated plate 15. In order not to obstruct the perforations of the latter the supporting face of the fin is beveled to an edge 90 20 which is interrupted at intervals by cross channels 21 to facilitate the escape of the liquid. Obviously if the plate is strong enough to stand the strains of the press without this auxiliary support, the fins may 95 be carried from the rim to the gear supporting ledge 23 entirely out of contact with the plate. The gear ring 22 is slipped over the ledge 23 and bolted in position substantially as shown.

100 The use of a perforated plate 15 of the character described, is an advantage from the standpoint of efficient drainage, since it is possible to use a plate having a much larger number of drainage holes than it is 105 practically possible to form in the old style web. This additional drainage results in more complete and rapid drying of the wet grains as they pass through the press. Again, since the liquid finds a ready outlet 110

there is less expense in power required to operate the press. There is no clogging. An obvious advantage also lies in the facilitation of repairs, and cleansing, since the 5 plate 15 may be taken out through the door of the press in like manner as the segmental screen described in my patent above mentioned. By reason of the fact that the plate is of less weight than the old web, 10 there is less frictional wear on the disk bearings and consequently longer life for the press. Furthermore, as above mentioned, it is possible to make the plate out of metal different from that of the body of the disk 15 and of such nature that it is not affected by the acids of the liquid coming from the mash grains. For this purpose bronze may be utilized, thus materially increasing the life of the disk.

20 I claim as my invention:—

1. A pressure disk for a rotary press of the character described, comprising hub, rim and interconnecting radial ribs dividing the disk into a plurality of segments, a 25 seating around the inner periphery of each segment, a removable perforated plate segment resting in the seating in each segment, together with an independent superposed screen overlying the plate in each segment, 30 substantially as described.

2. A pressure disk for a rotary press of the character described, comprising hub, rim and interconnecting radial ribs dividing the disk into a plurality of segments, a 35 seating around the inner periphery of each segment, a removable perforated plate segment resting in the seating in each segment, and having its outer face substantially flush with the face of the disk, together with an 40 independent superposed screen overlying the plate in each segment, substantially as described.

3. A pressure disk for a rotary press of the character described, comprising hub, 45 rim and interconnecting radial ribs dividing the disk into a plurality of segments, a seating around the inner periphery of each segment, a removable perforated plate segment resting in the seating in each segment, 50 together with an independent superposed screen overlying the plate in each segment, and forming the means for retaining said 55 perforated plate in its seating, and readily detachable means for securing said screen in position, substantially as described.

4. A pressure disk for a rotary press of the character described, comprising hub, rim and interconnecting radial ribs dividing the disk into a plurality of segments, a 60 gear ring supporting ledge on the rear face of the disk and spaced radially inward from the disk rim, together with strengthening ribs extending between said rim and ledge, substantially as described.

65 5. A pressure disk for a rotary press of

the character described, comprising hub, rim and interconnecting radial ribs dividing the disk into a plurality of segments, a gear ring supporting ledge on the rear face of the disk and spaced radially inward 70 from the disk rim, together with strengthening ribs extending between said rim and ledge, removable segmental perforated plates supported on the face of the disk between the radial ribs, said strengthening 75 ribs forming auxiliary supports for said plates, substantially as described.

6. A pressure disk for a rotary press of the character described, comprising hub, rim and interconnecting radial ribs dividing 80 the disk into a plurality of segments, a gear ring supporting ledge on the rear face of the disk and spaced radially inward from the disk rim, together with strengthening ribs extending between said rim 85 and ledge, removable segmental perforated plates supported on the face of the disk between the radial ribs, said strengthening ribs forming auxiliary supports for said plates, the supporting faces of said strengthening 90 ribs being beveled to an edge for the purpose described.

7. A pressure disk for a rotary press of the character described, comprising hub, rim and interconnecting radial ribs dividing 95 the disk into a plurality of segments, a gear ring supporting ledge on the rear face of the disk and spaced radially inward from the disk rim, together with strengthening ribs extending between said rim 100 and ledge, removable segmental perforated plates supported on the face of the disk between the radial ribs, said strengthening ribs forming auxiliary supports for said plates, the supporting faces of said strengthening 105 ribs being beveled to an edge and cross channeled for the purpose described.

8. In a press of the character described, a skeleton disk having hub, rim and interconnecting ribs forming a plurality of segments with open fields between the ribs, in 110 combination with a plurality of independent perforated plates removably supported on said disk and forming a readily detachable web between the hub and rim, for the 115 purpose described.

9. In a press of the character described, a skeleton disk having hub, rim and interconnecting ribs forming a plurality of segments with open fields between the ribs, in 120 combination with a plurality of independent perforated plates removably supported on said disk and forming a readily detachable web between the hub and rim, together with fine screens overlying said perforated 125 plates, for the purpose described.

10. In a press of the character described, a skeleton disk having hub, rim and interconnecting ribs forming a plurality of segments with open fields, said disk having 130

seats formed therein for the reception of readily-removable sectional web screens.

11. In a press of the character described, a skeleton disk having hub, rim and inter-
5 connecting ribs forming a plurality of seg-
ments with open fields between the ribs, in
combination with perforated plate means
removably supported on said disk and form-
ing a readily detachable web between the
10 hub and rim, said web being made of ma-

terial substantially unaffected by the acids
of a weak beer wort.

In testimony whereof I have signed my
name to this specification, in the presence
of two subscribing witnesses.
